UNITED STATES PATENT OFFICE

HUGH M. COOK, OF NEW YORK, N. Y., AND LOEILYS R. ROGERS, OF COTTAGE HILL,
FLORIDA, ASSIGNEES TO WALES DOVE-HERMISTON CORPORATION, OF NEW YORK,
N. Y., A CORPORATION OF NEW YORK

APPARATUS FOR COATING PIPES

Application filed July 17, 1929. Serial No. 379,002.

This invention relates to an improved apparatus for coating pipe and has particularly to do with the coating of large pipe such as employed in underground mains.

5 The object of the invention is to provide a convenient and efficient means whereby the outside of the pipe is conveniently covered or coated with a waterproofing composition such as bitumen, asphaltum, or compositions which are applied hot and which cool and 10 form a complete coating or covering for pipe that will protect the same from injurious contact with the ground.

In laying pipe lines, and particularly those 15 underground, it is a slow, laborious, more or less unsatisfactory method such as heretofore employed in coating these pipes. They are coated unevenly and the work is laborious and not by any means satisfactory.

20 It is therefore the broad object of our improved apparatus to greatly improve the operation and the results accomplished and save time and labor.

With these and other objects in view, the 25 invention consists in certain novel features of construction and combinations and arrangements of parts which will be more fully hereinafter described and pointed out in the claims.

30 In the accompanying drawings—

Figure 1 is a broken view in side elevation illustrating our improved apparatus;

Figure 2 is a view taken in section on the line 2—2 of Figure 1 showing the apparatus 35 in operation.

1, 1 represent base irons, which may be channels, as shown, and on which angle bars 2, 2 are rigidly secured. These angle bars 2, 2 receive bolts 3 secured by nuts 4, and on 40 these bolts between the pairs of angle bars 2, 2 rollers 5, 5 are mounted to turn.

These rollers are preferably arranged in pairs, and the pairs are spaced apart the desired distance, and said rollers preferably 45 have flanges 6 at their outer ends so that when a pipe 7 is positioned on the four rollers, as clearly indicated in Figure 1, the flanges 6 will prevent longitudinal movement of the pipe.

50 One pair of bars 1, 1 support parallel

upright frames 8, 8 having a bearing sleeve 9 at their upper ends and supporting a shaft 10 having a crank arm 11 at its outer end.

A sprocket wheel 12 is provided on the inner end of the shaft 10 and a sprocket 55 chain 13 is passed around the sprocket wheel 12 and around sprocket wheels 14 fixed to turn with two of the rollers at one end of the apparatus, as clearly indicated in the drawings.

With the parts as illustrated and assuming that a pipe 7 is positioned on the rollers 5, the operation is as follows, reference 60 being made to Figure 2 of the drawings:

One workman pours from a can or other 65 receptacle 15 a coating material 16 onto the upper portion of the pipe 7 as the latter is turned by the crank arm 11. Another workman holds a sheet or pad of asbestos or other analogous material against the coated pipe 70 so as to prevent an excessive flow of the coating material and to insure the even distribution of the same over the surface of the pipe. The workmen move longitudinally of the 75 pipe throughout the coating operation so that when one portion of the pipe is completely coated they move longitudinally of the pipe to allow another application of the material throughout the circumference or exterior of the pipe and thus apply the material in a 80 more or less spiral form.

While we refer to the pouring apparatus as a can or receptacle it is obvious it may take any other form which will allow the material to flow while hot on to the pipe, and 85 we may use any suitable means for insuring a proper spreading of the material and the escape of excessive material but we believe that a preferable application is such as above described, utilizing two workmen, one applying the liquid and the other causing it to 90 spread evenly as the pipe is revolved.

Various changes and alterations might be 95 made in the general form of the parts described without departing from our invention and hence we do not limit ourselves to the precise details set forth but consider ourselves at liberty to make such changes and alterations as fairly fall within the spirit and scope of the appended claims.

We claim:

1. An apparatus for facilitating the coating of pipe, comprising a pair of independent supports adapted to be positioned in longitudinal alinement, and a pair of pipe supporting rollers on each support adapted to receive and permit rotary movement of a pipe removably mounted thereon, said rollers having flanges thereon preventing longitudinal movement of the pipe.
- 10 2. An apparatus for facilitating the coating of pipe, comprising a pair of independent supports adapted to be positioned in longitudinal alinement, a pair of pipe supporting rollers on each support adapted to receive and permit rotary movement of a pipe removably mounted thereon, and means for positively turning at least one of said rollers to permit rotary movement of the pipe.
- 15 3. An apparatus for facilitating the coating of pipe, comprising a pair of independent supports adapted to be positioned in longitudinal alinement, a pair of pipe supporting rollers on each support adapted to receive and permit rotary movement of a pipe removably mounted thereon, said rollers having flanges thereon preventing longitudinal movement of the pipe, and means for positively turning at least one of said rollers to permit rotary movement of the pipe.
